UNITED STATES PATENT OFFICE.

LARS PARKER, OF CHICAGO, ILLINOIS, ASSIGNOR TO QUALITY HARDWARE & MACHINE CO., A COPARTNERSHIP CONSISTING OF HILDING A. LAYSTROM, JERRY ANDERSON, CARL SCHWARTZ, AND ELSIE LAYSTROM, ALL OF CHICAGO, ILLINOIS.

HYDRAULIC PRESS.

Application filed March 7, 1927. Serial No. 173,282.

This invention relates to a hydraulic press which is primarily adapted for forming angle pipes or tubes or the like.

The invention primarily consists in certain improvements whereby the fluid is more effectively controlled so as to avoid the loss of pressure or the escape of fluid and in which provision is made for relieving excess pressure.

10 The invention comprises the novel structure and combination of parts hereinafter described and more particularly pointed out and defined in the appended claims.

15 In the accompanying drawings which illustrate a preferred embodiment of this invention and in which similar reference numerals refer to similar features in the different views:

On the drawings:

20 Figure 1 is an elevational view of a hydraulic press involving this invention.

Figure 2 is an enlarged sectional view taken upon the line II—II of Figure 1, showing parts in elevation.

25 Figure 3 is an enlarged sectional view taken upon the line III—III of Figure 4 looking in the directions of the arrows.

Figure 4 is an enlarged vertical and central sectional view of a part of the hydraulic 30 press.

Figure 5 is an enlarged sectional view taken upon the line V—V of Figure 4.

Figure 6 is an enlarged sectional view taken upon the line VI—VI of Figure 2.

35 Figure 7 is an enlarged sectional view taken upon the line VII—VII of Figure 4.

Figure 8 is an enlarged sectional view taken upon the line VIII—VIII of Figure 4.

40 Figure 9 is an enlarged sectional view taken upon the line IX—IX of Figure 4.

Figure 10 is an enlarged fragmentary sectional view taken upon the line X—X of Figure 7.

45 As shown on the drawings:

As illustrative of this invention there is shown a hydraulic press comprising a base 1 upon which a die block 2 is positioned. The die block consists of a pair of connected members 2^a and 2^b which may be releasably held together by suitable latching mechanism. A die 3 is secured in the usual

aperture of the die block. This die has a cavity 4 which terminates at its lower end in an angular leg 5. It will be noted that 55 a metal tube 6 extends into this cavity for the purpose of forming an angular leg thereon through hydraulic pressure.

A plunger 7 provided with a central bore 8 which is automatically closed by a spring 60 pressed automatic valve 9 is adapted to supply the fluid to the cavity in the die. It will be noted that a resilient spring 10, the tension of which may be adjusted by a nut 11 and which is located in a valve head, acts 65 upon the ball valve 9. The tension of this spring is, however, adapted to be overcome by the pressure of the fluid. The lower end of the plunger is provided with a sleeve 12 which is slidably mounted thereon. The 70 upper end of the sleeve is provided with a pair of inwardly directed lugs or shoulders 13 which operate in cooperating grooves 14 in the plunger. The lower ends of the grooves and the lugs 13 form contacting 75 shoulders for supporting the sleeve with its lower end flush with the end of the plunger. A resilient spring 15 is confined in each groove and acts upon the top of the lug 13 in such groove for projecting the sleeve 80 downwardly. The lower end of the plunger 7 carries a cap 16 of rawhide or the like which is suitably affixed thereto and which is of such a size as to fit within the cylindrical sleeve 12.

85 It will be noted that the cylindrical sleeve 12 has the same diameter as the mouth of the tube 6 and that on account of the relative movement of the sleeve and plunger, the lower end of the plunger may be forced into 90 said tube 6 to a considerable extent as indicated by dotted lines in Figure 4 whereby leakage or loss of pressure is prevented.

It will be noted that the automatic valve 9 is located in a cylindrical boss 17 upon 95 the plunger. This boss is secured to the bottom of a fluid housing 18. The upper end of the plunger extends into and through the fluid housing. A pressure head 19 fits into the upper end of the fluid housing. 100 This pressure head is provided with a central bore 20 which extends inwardly from its lower end. A plurality of fluid passages 21 extend upwardly in the pressure head

and communicate with the upper end of the central bore for supplying fluid thereto. It will be noted that the upper part of the plunger 7 fits into the central bore of the pressure head and the central bore 8 of the plunger and the passages 21 provide communication between the pressure head and plunger.

The aforementioned housing is provided with means surrounding its upper margin for forming a water inlet chamber 22. This chamber is preferably formed from a sheet metal member which is stamped into cylindrical form with a pair of parallel flanges directed inwardly, the upper flange 23 being wider than the lower flange 24 which is secured against the side of the housing 18. The upper flange 23 forms an aperture for receiving the pressure head 19. The annular chamber 22 communicates with the interior of the housing by a plurality of oblique passages or ducts 25 shown in Figures 7 and 10.

Means are provided for releasably sustaining the pressure head above the ducts 25 as shown in Figure 4. To this end the lower end of the pressure head is provided with a groove 26 having an upper beveled surface 27 as clearly shown in Figure 10. A plurality of pins 28 having upper beveled surfaces corresponding to the beveled surface 27 of the groove 26 are located in suitable apertures adjacent the upper margin of the fluid housing. Each aperture communicates with a downwardly extending recess in the fluid housing in which a retaining pin 29 is secured. These retaining pins have inner beveled edges which engage suitable notches in the pins 28. The pins 29 have their lower ends beveled as shown in Figure 1 for co-operating with plunger pins 30 which are supported in small cylinders 31 screwed into the housing. It will be noted that the ends of these cylinders are closed by adjustable plugs 32 and that coil springs 33 are confined between such plugs and the ends of the retaining pins 30. Consequently, when pressure is applied upon the pressure head, a camming action will occur between the sloping surface 27 of the cam groove 26 and the beveled edges of the pins 28. This pressure will be sufficient to drive the pins 28 in a radial direction outwardly. At the same time the retaining pins 29 will be forced downwardly on account of the sloping surfaces between them and the pins 28. As the pins 29 are forced downwardly the plunger pins 30 will of course be forced outwardly against the tension of the springs 33.

Circumferentially of the lower part of the fluid housing there are a plurality of relief cylinders 34 which communicate with the interior of the housing by means of ducts 35 and which communicate with the annular inlet water chamber through suitable connecting pipes 36. The outer end of each pas-

sage 35 is closed by a ball valve 37. Each ball valve is sustained by a suitable plate 38. The outer ends of the relief cylinders 34 are closed by adjustable plugs 39 and stiff coil springs 40 are confined between the plugs and the plates 38. The springs 40 are designed with sufficient tension to withstand the normal amount of required pressure during the operation of pressing the tube. However, if the fluid pressure should be increased beyond a safe limit for some reason, the tension of the springs 40 would be overcome, allowing the water to escape through the relief valves and back into the annular fluid inlet chamber thuswise relieving the excess pressure. Any suitable connection may be provided for supplying fluid to the fluid inlet chamber and in the present instance, there is shown a pipe 41 which may be connected to the source of fluid supply.

It will, of course, be understood that the pressure head is designed to be forced down by any suitable power means. In the present instance, I have shown the same extending into a pressure cylinder 42 of a hydraulic press (Figure 1). It is of course, to be understood that any other power means may be used.

In the operation of the hydraulic press, the tube that is to be elongated or formed with a bend is inserted in the die. The plunger 7 is then lowered until the sleeve engages the top of the tube 6. It will, of course, be assumed that the pressure head is held by the yielding detents 28, 29 and 30, as shown in Figure 4. Fluid may now be admitted to the fluid housing 18 and the fluid pressure may be applied to the fluid head 19. As soon as the pressure is thuswise applied to the fluid head, the housing will descend until the plunger enters the tube 6 as shown in dotted lines in Figure 4. During this movement, the pressure head will be released for entering the fluid housing 18 and compressing the fluid which will emerge through the passages 21 into the central bore 8 of the plunger and down into the tube 6, the ball valve 9 being automatically opened by the pressure of the fluid. Under sufficient pressure, the tube will be properly formed, the pressure of the fluid extending the same into the angle leg of the die as is obvious. When the pressure is released, the valve 9 will automatically close preventing the escape of fluid from the housing and the pressure of the water will automatically return the pressure head to the position shown in Figure 4, the yielding detents 28 being automatically snapped into the groove of the pressure head by the pins 29 and 30 due to the force of the springs 33.

I am aware that many changes may be made and numerous details of construction may be varied through a wide range without departing from the principles of this

invention and I, therefore, do not purpose limiting the patent granted hereon, otherwise than necessitated by the prior art.

I claim as my invention:

- 5 1. In a machine of the character described, the combination with a die having a forming cavity for receiving a tube, of a plunger adapted for fitting in said tube and a sleeve on the lower end of said plunger adapted 10 for resting on said tube, said sleeve and plunger having relative movement whereby said plunger may enter said tube for the purpose set forth.
- 15 2. In a machine of the character described, a plunger having an axial bore, a sleeve slidably mounted upon said plunger, said sleeve and plunger having coacting shoul-

ders and resilient means tending to maintain said shoulders in engagement.

3. In a machine of the character described, 20 a plunger having an axial bore, a sleeve mounted upon the lower end of said plunger for relative sliding movement and yielding means acting upon said sleeve.

4. In a machine of the character described, 25 the combination with a die having a forming cavity for receiving a tube, of a plunger adapted for fitting in said tube and means surrounding said plunger for abutting relation with said tube for preventing the escape 30 of fluid.

In testimony whereof I have hereunto subscribed my name.

LARS PARKER.
